UNITED STATES PATENT OFFICE.

GEORGE J. CAPEWELL, OF HARTFORD, CONNECTICUT.

DESIGN FOR A RAILWAY-CAR BODY.

SPECIFICATION forming part of Design No. 32,369, dated March 20, 1900.

Application filed December 12, 1899. Serial No. 740,132. Term of patent 14 years.

To all whom it may concern:

Be it known that I, GEORGE J. CAPEWELL, a citizen of the United States, residing at Hartford, in the county of Hartford and State 5 of Connecticut, have invented a certain new and original Design for Railway-Car Bodies, of which the following is a specification.

Referring to the accompanying drawings, Figure 1 shows a plan view of a car-body built according to my design. Fig. 2 shows a side elevation of this car-body, and Fig. 3 shows an end view of the car-body.

As shown in the drawings, the leading or material feature of my design is the oblong body, that has a substantially smooth round top that curves downwardly toward each end and that has practically smooth sides which recede toward each end.

The portion of the body 1 that contains the 20 windows 2 between the doors 3 in cross-sec-

tion is approximately semicylindrical, as illustrated in Fig. 3. Beyond the doors the top of the body curves downwardly toward the ends, as illustrated in Fig. 2, and the sides of the body beyond the doors curve toward each other, so as to form wedge-shaped ends, as illustrated in Fig. 1.

Having now described my invention, what I claim as new, and desire to secure by Letters Patent, is—

The design for a car-body herein shown and described.

In testimony whereof I have signed my name to this specification in the presence of two subscribing witnesses.

GEORGE J. CAPEWELL.
